FRUIT ENGAGING ELEMENT FOR USE IN A CONVEYOR FOR HANDLING AND SIZING FRUIT

Maurice V. Johnson, Jr., Upland, Calif., assignor to Sun-kist Growers, Inc., Los Angeles, Calif., a corporation of California

Filed Jan. 20, 1964, Ser. No. 78,273

Term of patent 14 years

(Cl. D54—13)

FIG. 1.

FIG. 2.

FIG. 3.

FIG. 1 is a side elevation of a fruit engaging element for use in a conveyor for handling and sizing fruit, showing my new design;

FIG. 2 is an elevational view of one end thereof; and

FIG. 3 is an elevational view of the other end thereof.

I claim:

The ornamental design for a fruit engaging element for use in a conveyor for handling and sizing fruit, as shown.
